ATTORNEY

J. G. Evans, Jr.
WITNESS:

UNITED STATES PATENT OFFICE.

ROBERT M. EDINGTON, OF VINELAND, NEW JERSEY.

POULTRY DRINKING FOUNTAIN.

Application filed August 11, 1924, Serial No. 731,428. Renewed June 18, 1926.

This invention relates to drinking fountains, and an object of the invention is to provide a drinking fountain particularly designed for use by poultry raisers, so as to enable the poultry to obtain fresh, clean drinking water at any time, and also to provide a fountain which will prevent needless waste of water.

Other objects of the invention will appear in the following detail description, and in the accompanying drawings wherein:

Figure 1 is a vertical section through the improved drinking fountain.

Figure 2 is a top plan of the improved drinking fountain.

Referring more particularly to the drawings, the improved drinking fountain comprises the lower bowl 1 which has a central sleeve 2 formed internally therewith. The sleeve 2 is internally screw-threaded, as shown at 4, to permit connection therewith of a water supply pipe and also to receive therein the threaded cylindrical body 5 of the valve structure which controls the flow 25 of the water into the upper drinking bowl 6. The upper drinking bowl 6 is smaller in diameter than the lower overflow bowl 1, and it may have a plurality of slight cut-away portions 7 in its upper edge and outer surface to facilitate the drinking or overflow of water from the upper drinking bowl 6 into the lower overflow bowl 1. The needle valve structure 5 is threaded into the central bosses 8 on the drinking bowl 6, and it serves to connect the drinking bowl to the overflow bowl. The valve structure 5 includes the central duct 9 and the transverse outlet duct 10. The flow of water through the ducts 9 and 10 is controlled by the adjustable needle 11.

A screen 12 is placed within the overflow bowl 1 upwardly from the bottom thereof, so as to prevent any foreign matter from flowing through the outlet 13 and clogging up the outlet.

The drinking bowl 6 is detachably connected to the valve structure 5 and through

the valve structure to the overflow bowl 1 so as to permit it to be quickly and easily removed for purposes of cleaning and sterilization. The upper projecting end of the valve 5 is of substantially the same diameter as the innermost bore of the threads in the collar 8 of the bowl 6, so as to serve as a guide when replacing the bowl 6 after it has been removed, thereby materially increasing the longevity of the device by eliminating liability of improper engagement of the threads. If it is so desired, a gasket or washer may be placed between the collars 2 and 8.

It is, of course, to be understood, that the invention may be constructed in various other manners and the parts associated in different relations, and therefore, I do not desire to be limited in any manner, except as set forth in the claims hereunto appended.

What I claim is:

1. A drinking fountain comprising an overflow bowl having a water supply pipe connected therewith, a centrally disposed boss extending into said overflow bowl, a drinking bowl smaller in diameter than the overflow bowl, a depending boss on the drinking bowl, a valve structure connecting said drinking bowl to said overflow bowl, and adapted to regulate the flow of water into the drinking bowl.

2. A drinking fountain comprising an overflow bowl having a water supply pipe connected therewith, a centrally disposed boss extending into said overflow bowl, a drinking bowl smaller in diameter than the overflow bowl, a depending boss on the drinking bowl, a valve structure connecting said drinking bowl to said overflow bowl, and adapted to regulate the flow of water into the drinking bowl, and a filtering screen within the overflow bowl and resting upon said central boss.

In testimony whereof I affix my signature.

ROBERT M. EDINGTON.
